Primary Examiner—Dominic Simone

(74) Attorney, Agent, or Firm—Banner & Witcoff, Ltd.

(57) CLAIM

The ornamental design for a portion of a shoe upper, as shown and described.

DESCRIPTION

FIG. 1 is a perspective view of a portion of a shoe upper showing my new design;

FIG. 2 is a side elevational view thereof;

FIG. 3 is a front elevational view thereof;

FIG. 4 is a rear elevational view thereof; and,

FIG. 5 is a top plan view thereof.

The broken line showing the remainder of the shoe is for illustrative purposes only and forms no part of the claimed design.
